CLAIM

The ornamental design for fishing spoon with rattle, as shown and described.

DESCRIPTION

FIG. 1 is a perspective view, viewed generally from the bottom of a fishing spoon with rattle, showing my new design;

FIG. 2 is a right side view thereof, the left side being a mirror image;

FIG. 3 is a top plan view thereof;

FIG. 4 is a bottom plan view thereof; and

FIG. 5 is a rear elevational view thereof; and,

FIG. 6 is a front elevational view thereof.
